UNITED STATES PATENT OFFICE.

CHARLES H. QUINN, OF ROANOKE, VIRGINIA.

RAILROAD TURN-TABLE SAFETY MECHANISM.

1,244,241.

Specification of Letters Patent.

Patented Oct. 23, 1917.

Application filed August 17, 1916. Serial No. 115,549.

To all whom it may concern:

Be it known that I, CHARLES H. QUINN, a citizen of the United States, residing at Roanoke, in the county of Roanoke and 5 State of Virginia, have invented certain new and useful Improvements in Railroad Turn-Table Safety Mechanism, of which the following is a specification.

This invention relates to turntables such 10 as used for turning locomotives and cars, and the object thereof is to provide safety means for preventing railway vehicles running off the end of a lead track and dropping into the turntable pit at such time 15 when the bridge track is out of registry with the lead track, and to prevent workmen and others from stepping into the turntable pit.

The invention consists of the formation, combination and arrangement of parts as 20 will be herein described and finally claimed.

In the drawings, Figure 1 is a plan view showing a turntable fitted in accordance with the present invention. Fig. 2 is a vertical-sectional view taken through the 25 turntable pit, this section being taken approximately on the center line of the pit, but with the turntable itself in elevation. Fig. 3 is a vertical-sectional view taken adjacent the derail-actuating mechanism and 30 substantially on the line 3—3 of Fig. 1. Fig. 4 is a partial plan view showing an alternative arrangement of the vehicle derail or stop in the lead track.

Referring to these drawings, the circular 35 turntable pit is shown at 5 and there is disposed within this the passageway or bridge 6, which is carried on the customary center pivot 7. Such turntables are supplied with some means for their rotation, either for 40 hand or power use, a motor cab 27 being shown and a driven tractor wheel 28 for driving coöperation with the concentric rail 26 on the floor of the pit. Thus the bridge is capable of assuming any diametrical position 45 across the circular pit. The bridge 6 carries a car track 8 and one or more external lead tracks 9—10 lead up to the turn-table pit and end in positions where the bridge track may be brought into registry 50 with them so as to provide a way of entrance to or exit from the bridge 6.

It frequently happens that rolling stock 55 is pushed out of one of the lead tracks when the bridge track is out of registry with the lead track and the vehicle may then be run off into the pit, causing serious damage.

The invention is directed in part to means for preventing such accidents. To this end I provide in a lead track a derailing mechanism, or stop such as shown in the track 60 10. This consists of an obstruction 11 so set as to normally prevent traffic toward the pit 5. I then provide means for automatically moving this stop or derail away from the rail so as to permit traffic toward 65 the pit and this shifting of the derail is controlled by the bridge 6 in such manner that the derail will be moved as stated only when the bridge track is in registry with the particular lead track.

The derail may preferably be moved by means of an air cylinder 12 supplied with air under pressure from a source 13. A three-way valve 14 is located in the line so that in one position the air from 13 will be 70 admitted to the cylinder 12 and when in the other position the air from 13 will be shut off and the cylinder may exhaust and the piston thereof retreat so as to allow the derail to seat against the rail.

The three-way valve 14 is preferably operated by means of a magnetic switch 15 suitably wired at 16 and 17 to contacts 18 and 19 located at any suitable place such as on the floor of the pit 5. The bridge 6 85 then carries a shoe or contactor 20 which bridges the gap between 18 and 19 just when the tracks register. Batteries such as 30 may be used as a source of current for energizing the switch 15. Thus at the proper time the 90 derail will be removed and traffic may move toward the pit 5. A suitable switch 29 may be located in the wiring so as to cut out the operation of the mechanism whenever desired.

On leaving the bridge it is not desirable that the bridge remain in registering position until the last wheels of the vehicle have passed the derail, hence the derail is so constructed that traffic may at all times move 100 unhindered away from the pit. A spring switch stop or derail such as shown in Fig. 1 or a spring switch turn-out such as shown in Fig. 5 is preferably used, the derail in the first instance either stopping the vehicle or 105 landing the same on the ground and in the second instance switching it to another track.

The spring 21 for the derail may be located in the connection 22 between the piston of the air cylinder 12 and the derail and serves to allow the vehicle wheels to spring 110

the stop away from the rail when traveling away from the pit. Thus has been provided safety means to prevent vehicles dropping into the pit. There remains to provide 5 means to prevent workmen from stepping into the same, and in my mechanism this consists of a circular guard or rail 23 which surrounds the pit and is attached to and rotates with the bridge by means of any suitable braces such as 24. This guard has a 10 suitable opening to allow entrance to the bridge at each end, these not interfering with the safety feature, as the bridge platform is usually flush with the surface around 15 the pit. The guard 23 is preferably carried on wheels or rollers 25 which run on the concentric, circular, motor track 26 on the bottom of the pit and near its edge. And the guard rail is also preferably made 20 with some vertical flexibility with respect to the bridge so as to allow tilting of the bridge and for irregularities in the track, the braces 24 being hingedly connected so as to allow this vertical flexibility.

25 I have thus described an embodiment of my complete invention. It will be recognized that other embodiments are possible within the scope of the appended claims without departing from the spirit thereof.

30 What I claim is:

1. In a turntable arrangement, a movable bridge carrying a car track, a track external thereof and leading thereto, means for moving the said bridge into a position to bring 35 the two tracks into registry, a traffic stop in the external track and normally blocking the same against traffic toward the bridge, a source of power and means for moving the said stop, an electric circuit, means carried 40 by the bridge for breaking the said circuit when the said tracks are out of registry and for completing the circuit when the same are in registry, and a magnetic switch in said circuit controlling the application of the 45 power to the said stop-moving means in such manner that the power will be admitted to clear the said lead track when the said electric switch is magnetized and will be shut off to block the lead track when the 50 electric switch is demagnetized.

2. In a turntable arrangement, a movable bridge carrying a car track, a track external thereof and leading thereto, means for moving the said bridge into a position to bring 55 the two tracks into registry, a traffic stop in the external track and normally blocking the

same against traffic toward the bridge, a source of fluid pressure and a fluid-pressure motor for moving the said stop to clear the lead track, an electric circuit, means carried 60 by the bridge for breaking the said circuit when the said tracks are out of registry and for completing the circuit when the same are in registry, and a magnetic switch in said circuit controlling the admission of the 65 fluid pressure to the said fluid-pressure motor, the parts being so formed that fluid pressure will be admitted when the magnetic switch is magnetized and cut off when the same is demagnetized. 70

3. In a turntable arrangement, a circular pit, a bridge pivoted therein and centrally therewith and forming a rotatable, diametrically-disposed, passageway across the said pit, and a guard rail encircling the said pit 75 and carried practically by the said bridge and rotatable therewith, the said guard rail being cut away at the ends of the said bridge, there being additional means within the pit coöperating with the bridge to support the 80 said guard rail, the latter being supplied with supports adapted to engage the additional supporting means.

4. In a turntable arrangement, a circular pit, a bridge pivoted centrally therein and forming a diametrically-disposed, rotatable passageway across the said pit, a guard rail 85 encircling the said pit and carried by the said bridge and being rotatable therewith, a runway rail laid in a circular path concentric with the said pit, and wheels supporting the said guard rail and traveling on the said runway rail. 90

5. In a turntable arrangement, a circular pit, a bridge pivoted centrally therein and 95 forming a diametrically-disposed, rotatable passageway across the said pit, a guard rail encircling the said pit and carried by the said bridge and being rotatable therewith, a runway rail laid in a circular path concentric with the said pit, and wheels supporting the said guard rail and traveling on the said runway rail, the said guard rail being secured to the said bridge in such manner as 100 to allow vertical flexibility therebetween. 105

In testimony whereof I affix my signature in presence of two witnesses.

CHARLES H. QUINN.
